UNITED STATES PATENT OFFICE

MATIAS MORALES, OF TAMPA, FLORIDA

SANDWICH HOLDER

Application filed October 16, 1930. Serial No. 489,183.

This invention relates to a sandwich holder whereby direct contact of a sandwich with the hands or gloves of the user can be prevented so that tourists and others purchasing 5 sandwiches can eat them without soiling the hands or gloves or, if the hands are soiled, can keep the sandwich clean while it is being eaten.

Another object is to provide a sandwich 10 holder which is inexpensive and can be discarded after use.

Another object is to provide a device of 15 this character which can be quickly applied to a sandwich and will remain properly assembled therewith as long as desired.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without departing 25 from the spirit of the invention.

In the accompanying drawing the preferred form of the invention has been shown.

In said drawing:

Figure 1 is a plan view of the blank from 30 which the holder is made.

Figure 2 is an end elevation of the blank after it has been partly shaped for use.

Figure 3 is an end view showing the holder 35 partly folded into position for housing a portion of a sandwich.

Figure 4 shows the holder completely folded with its opposed portions interlocked.

Figure 5 is a section on line 5-5, Figure 4, a portion of a sandwich being indicated by 40 broken lines.

Referring to the figures by characters of reference, 1 designates a blank formed of cardboard or other suitable material so shaped as to provide an elongated intermediate portion 2 separated by score lines 3 or the like from oppositely extending angular wings 4. Each of these angular wings has a flap 5 extending from the base thereof, the flap being of the same length as the base 50 and being provided at an intermediate point

with a diagonally disposed slit 6 extending to an opening 7.

An elongated tongue 8 is produced in the intermediate portion 2 by cutting a slit into said portion as shown at 9.

Obviously the device herein described can be cut readily from a sheet of cardboard or the like. When it is desired to use one of the holders it is bent along the score lines 3 and also along score lines 10 which are provided between the wings 4 and the flaps 5. After the holder has been brought substantially to the position shown in Figure 2 with the flaps 5 lapping, the sandwich S is placed against the intermediate portion 2 and between wings 4. The wings are then placed against opposed sides of the inserted sandwich and the slotted portions of the flaps 5 are caused to interfit as shown in Figure 4. Thus the sandwich will be completely housed 70 at one corner and can be handled readily while the exposed portion is being eaten.

When it is desired to eat that portion which is housed in the holder the user presses against the tongue 8 with a finger so as to 75 cause the sandwich to be thrust gradually from the holder. This operation can continue until the entire sandwich has been eaten after which the holder can be discarded.

What is claimed is:

1. A device for holding one corner portion of a sandwich to protect the hand of the user while the sandwich is being eaten, including a single blank of sheet material including an intermediate portion, side wings and lapping portions on the side wings, said portions and wings being bendable to form an angular holder open between the wings and opposite said intermediate portion for the protrusion of a portion of an article held between the wings.

2. A device for holding one corner portion of a sandwich to protect the hand of the user while the sandwich is being eaten, including a single blank of sheet material including an intermediate portion, side wings and lapping portions on the side wings, said portions and wings being bendable to form an angular holder open between the wings.

and opposite said intermediate portion for the protrusion of a portion of an article held between the wings, said lapping portions being provided with slits thereby to interlock and hold the wings against separation.

3. A device for holding one corner portion of a sandwich to protect the hand of the user while the sandwich is being eaten, including a single blank of sheet material including an intermediate portion, side wings and lapping portions on the side wings, said portions and wings being bendable to form an angular holder open between the wings and opposite said intermediate portion for the protrusion of a portion of an article held between the wings, and an ejecting tongue integral with said intermediate portion for engagement with one edge of the held article to slide the article bodily through the open portion of the holder.

In testimony that I claim the foregoing as my own, I have hereto affixed my signature.

MATIAS MORALES.
